UNITED STATES PATENT OFFICE.

WAICHI NAKAGAWA, OF KITAKU, JAPAN.

STEAM BOILER.

Application filed November 29, 1918. Serial No. 264,775.

To all whom it may concern:

Be it known that I, WAICHI NAKAGAWA, a subject of His Majesty, the Emperor of Japan, residing at No. 43-A Tomijimacho, 5 Kitaku, Osaka, Japan, have invented certain new and useful Improvements in Steam Boilers, of which the following is a specification.

This invention relates to improvements in 10 steam boilers of the horizontal fire tube type, and more particularly in steam boilers having horizontal fire chambers below the boiler shell and a separate combustion chamber.

15 It is the general object of the invention to provide a boiler of the type referred to, which is simple and efficient and particularly adapted for marine use.

In the drawings—

20 Fig. 1 is a front view of a construction embodying the invention; and

Figs. 2 and 3 are a side elevation and a rear view respectively thereof.

The arrangement preferably comprises a 25 plurality of tubular fire chambers or furnaces a^1 and a^2 in parallel relation and surrounded by annular water spaces. Above the furnaces is disposed the boiler shell b , which contains the usual fire tubes b^1 . The 30 arrangement of the furnaces and the boiler may be of any usual construction. The interspace between the shell b and the water spaces surrounding the furnaces a^1 and a^2 forms a passage for the products of combustion. At the rear of the furnaces and the boiler is a combustion chamber which, by means of a horizontal partition 9, is divided into a lower chamber 7 and an upper chamber 8. The lower chamber is in communication with the interspace mentioned and the upper chamber is in communication with the fire tubes of the boiler. A smoke box 6 at the front end of the boiler establishes a connection between the interspace 45 and the fire tubes.

The products of combustion are thus forced to pass from the furnace through the lower chamber 7, through the interspace and the smoke box 6 into and through the fire 50 tubes of the boiler and then pass through the chamber 8 into the flue 10 and thus come into intimate thermal contact with the water in the annular spaces surrounding the furnaces a^1 and a^2 and with the bottom of the boiler shell b aside from passing through the fire tubes.

In the combustion chamber 7 are mounted water drums w^1 and w^2 transversely of the furnaces, and in the chamber 8 are mounted two similar drums w^3 and w^4 . The drums are preferably connected in series by means of pipes 11. The lower drum w^1 is connected by a pipe m to the bottom of the annular waterspace surrounding the two furnaces a^1 and a^2 while the upper drum w^4 is 60 connected by a pipe n to the boiler approximately in the plane of the normal water level thereof. I also prefer to interconnect the upper part of the annular water space surrounding the furnaces with the boiler substantially at the normal water level thereof, as by means of pipes c .

Similarly the bottom of the annular water spaces may be in fluid connection, as by branches 1 and 2 and pipe d^1 , with the bottom of the boiler shell b .

In the chambers 7 and 8 I prefer to use baffles 12 for deflecting the products of combustion against the water drums.

The arrangement described brings about 80 a highly efficient heat exchange between the products of combustion and the water in the boiler and the thermal efficiency is increased by the different fluid connections allowing convection currents to flow between 85 different parts of the system.

I claim:—

1. A steam boiler comprising two lower cylindrical elements having each a furnace, an upper cylindrical element having a nest 90 of fire tubes, a smoke box at the front end of the said elements interconnecting the space between the three elements with the fire tube nest, a combustion chamber at the rear end of the said elements, a partition wall in the combustion chamber dividing it into an upper and a lower compartment in such a way that the lower compartment is in communication with the said space and the upper compartment with the rear end of the 95 fire tube nest, drums in the two compartments interconnected in series and fluid connections between the end drums and the said elements respectively.

2. Boiler construction according to claim 100 1 including baffle plates in the combustion chamber for directing the products of combustion against the drums.

In testimony whereof I affix my signature.

WAICHI NAKAGAWA.
